OVERHEAD MONORAIL SYSTEM

Alphonse F. Anjeskey, Cleveland, Ohio, assignor
to The Cleveland Crane & Engineering Com-
pany, Wickliffe, Ohio, a corporation of Ohio

Application August 9, 1950, Serial No. 178,402

15 Claims. (Cl. 104—98)

1

The present invention relates to material handling, overhead monorail carrier systems including an overhead transfer bridge or crane having a carrier rail adapted to be selectively aligned with a carrier rail of one or more stationary tracks, transfer bridges, cranes and, more particularly, to mechanism for locking or interlocking the transfer bridge or crane and the stationary track or other bridge or crane together with their respective carrier rails in end-to-end alignment in a vertical plane.

Heretofore transfer bridges and cranes have been locked relative to each other or to stationary tracks with their respective carrier rails in alignment so as to facilitate the movement of carriers to and from the transfer bridges, etc., with a minimum delay and attention on the part of the operators, by providing spring-pressed locking members slidably supported on the carrier bridge and having notches therein adapted to receive web members of the other tracks or bridges. Cooperating cam means on the respective structures is employed for moving the locking members against the pressure of the springs so that the web members could be engaged within the notches as the bridges or cranes are moved into alignment with the stationary tracks or other bridges, etc. The camming of the locking members against the action of the springs is effected by the movement of the bridges or cranes along their runways relative to the tracks or bridges, etc., with which it is to be aligned. Of necessity the force required to retract the locking members by the camming action referred to is considerable which make it difficult, if not impossible, to bring the bridges to a gradual and smooth stop with the respective carrier rails and the like. The bridges must be traveling at an appreciable rate so that they have sufficient momentum to provide the force necessary to actuate the lock members, with the result that when the web members engage in the notches the bridges are brought into an abrupt halt which often is detrimental to the loads on the carriers on the bridges and subjects the various parts of the system to severe shocks and undue strains.

Manually operable control mechanisms are provided for releasing the interlocks and/or moving them to an inoperative position, and when the lock members engage over the web members they impart a sudden movement to the control mechanisms, often to the inconvenience and possible injury of the operators.

The principal object of the present invention is the provision of a new and improved overhead

monorail carrier system having a transfer bridge or the like and mechanism for locking the bridge or the like against movement on its runway with its carrier rail in alignment with another carrier rail of the system, which mechanism includes a movable lock member, preferably on the bridge, adapted to be automatically moved to interlock with a part associated with the other carrier rail when the carrier rail of the bridge is aligned therewith, which automatic movement is effected without appreciable drag on the travel of the bridge whereby the bridge may be gradually and smoothly brought to a stop at the desired point.

Another object of the invention is the provision of a new and improved overhead monorail carrier system of the character referred to having a mechanism to lock the bridge or the like against movement along its runway with its carrier rail in alignment with another carrier rail of the system of which the bridge is a part and with respect to which the bridge has relative movement, which mechanism comprises a lock member, preferably on the bridge, adapted to interlock with a part associated with the other carrier rail when the rails are aligned and hold the rails in alignment, the lock member being yieldingly urged to interlocking position and retained in a retracted or non-locking position by a latch device adapted to be tripped by relative movement between the bridge and the other carrier rail to release the lock member when the two carrier rails are aligned.

Still another object of the invention is the provision of a new and improved overhead monorail carrier system of the character referred to having a mechanism to lock a traveling bridge or the like against movement along its runway, etc., and in alignment with another carrier rail of the system of which the bridge is a part and with respect to which the bridge has relative movement, which mechanism includes a lock member, preferably on the bridge, adapted to be automatically moved to interlock with a part associated with the other carrier rail when the carrier rails are aligned, and a control member for selectively rendering the locking member operative or inoperative, which control member has a lost-motion connection with the lock member so that the lock member may move to its interlocking position without causing corresponding movement of the control member.

A further object of the invention is the provision of a new and improved overhead monorail carrier system of the character referred to having mechanism to lock the traveling bridge or

the like in alignment with another carrier rail of the system of which the bridge is a part and with respect to which the bridge has relative movement, which mechanism includes a lock member, preferably on the traveling bridge, adapted to be set for yielding movement into locking engagement with a member associating with the other rail and to be withdrawn from locking engagement and/or selectively held in an inoperative position by a control member, and a latch operative to restrain the movable lock member in retracted position and from locking movement, which latch is automatically tripped to release the lock member to its locking position when the rails are aligned, the control member having a lost motion connection with the lock member so that when it is set to render the lock member operative the latter can be released by the latch and move to its locking position independently of the control member.

The invention resides in certain details of constructions and combinations and arrangements of parts and further objects and advantages thereof will be apparent to those skilled in the art to which the invention relates from the following description of the preferred embodiment described with reference to the accompanying drawings forming a part of this specification, in which similar reference characters designate corresponding parts, and in which;

Fig. 1 is a fragmentary side elevational view of a material handling overhead monorail carrier system embodying the invention;

Fig. 2 is a top plan view of the portion of the overhead carrier system shown in Fig. 1 part of which is broken away, and

Figs. 3 and 4 show portions of the carrier system similar to that shown in Fig. 1 but on a larger scale, Fig. 4 being a continuation of Fig. 3, as indicated by line 3—3.

As mentioned hereinbefore, the invention relates to an overhead monorail carrier system comprising mechanism for selectively securing a carrier rail on a traveling overhead crane or bridge in end-to-end alignment with another carrier rail of the system with respect to which the bridge has relative movement. In the preferred form of the invention shown, the locking mechanism includes a notched lock member carried by the bridge and arranged to be biased into interlocking engagement with a part of the other rail, or the support structure for the other rail, when the rails are brought into alignment. The lock member may be retracted from its interlocking position or set to be biased to its locking position by a control member, preferably carried on the bridge and movable between two positions to move the locking member as described. A latch is provided for restraining the lock member in its retracted or inoperative position and means is provided for automatically releasing or tripping the latch by movement of the bridge when the carrier rails are brought into alignment. The effort required to operate the latch is negligible so that the bridge may be brought to the rail aligning position slowly and smoothly.

Preferably, a lost motion connection is provided between the control member and the lock member so that the latter may move to its locking position without causing corresponding movement of the control member.

Referring now to the drawings, Fig. 1 is a view of a portion of an overhead monorail carrier system showing one end of a hand propelled overhead transfer bridge designated generally at A,

and an end portion of a stationary track support structure B. The transfer bridge A and structure B are shown in side elevation and positioned so that material handling carriers, not shown, can be transferred to and from the bridge from the structure B. The particular system illustrated is a hand propelled or hand powered system; in other words, the carriers and transfer bridge are propelled manually. However, the invention is not limited to this type of powered system and it may be used as well with an electrified system in which the carriers or transfer bridge, or both, are electrically powered.

The transfer bridge A comprises a track assembly including a girder 10 of T-section, to the lower part of which is welded a carrier rail 11 of inverted T-section, which rail forms the lower or tension member of the girder. The ends of the girder are suspended from end trucks 12, only one of which appears in the drawings, which trucks comprise wheels 14 rotatably supported by anti-friction bearings and swiveling wheel yokes connected to opposite ends of the load bars of the trucks. The wheels 14 engage opposite sides respectively of inverted T-section rails 15 suspended from an overhead structure in a suitable manner and which form a runway for the transfer bridge A. The particular means by which the runways for the bridge are supported forms no part of the present invention and suffice to say they are preferably flexibly suspended by hanger rods, not shown, to assist in relieving stresses, wheel flange friction, etc.

As is well understood in the art, the transfer bridge A is adapted to move along its runway and receive overhead carriers from an overhead rail and transfer the carriers to areas to pick up or discharge loads or to another overhead rail extending laterally of the bridge runway. The overhead rail or rails extending laterally of the bridge runway may be supported by stationary structures or by another transfer bridge or crane. In the embodiment shown, the structure B is stationary and comprises a T-girder 21 having an inverted T carrier rail 20 welded to the bottom thereof, which rail forms the lower tension member of the girder. As seen in Fig. 1, the girder 21 terminates short of the end of rail 20 and a plate P is welded to the end of the girder and to the top of the rail. The plate P is T-shaped and forms an integral part of the girder 21. Alternatively, the plate P could be eliminated and the girder and the rail could be coextensive.

The girder 21 is suitably supported so that the outer end of the rail 20 has the same elevation as the adjacent end of the bridge rail 11. The support structure for this purpose is not shown as it is not essential to the understanding of the present invention.

The bridge A is adapted to be locked against movement on its runway with the rails 11, 20 in end-to-end alignment by a locking member 26 which is adapted to interlock with a portion of the plate P when the rails are aligned. The member 26 has a flared notch 27 therein which is adapted to receive an edge portion of plate P, as seen in Figs. 1, 2, to interlock the member with the plate. The member 26 is attached to the ends of two rods 28, 29 and is adapted to be reciprocated between its interlocking and retracted positions, as illustrated in the broken and full lines, respectively, in Fig. 3, by these rods which are located on opposite sides of girder 10 and are each slidingly supported by two spaced guide bushings 30, 31. The bushings 30, 31 have

support plates or flanges 32, 33, which are bolted to the girders by bolts and nuts 31. The rods 28, 29 are each biased outwardly, or to the left as shown in Fig. 1, by a coil spring 38, only one of which is shown, which springs are carried on the rods and interposed between the bushings 31 and washers 39 which abut pins 40 on the rods. The springs 38 urge the rods outwardly so that the lock member 26 is normally biased to the position in which it interlocks with plate P.

The member 26 may be moved and held in its retracted or inoperative position by a control mechanism, and accordingly the inner ends of the rods 28, 29 are attached to an operating yoke 42 which is formed of complementary members 43, 44, attached together at one end by a threaded rod 46 extending through eyes in the ends of the members and nuts 47 threaded on the rod, as shown. The outer ends of the yoke members 43, 44 have eyes which receive the rods 28, 29, respectively, and are secured to these rods by nuts 49.

The rods 28, 29 may be moved to the right to retract the lock member 26 by a control mechanism which includes a link 51 connected with yoke 42, preferably by a lost motion connection. To this end rod 46 has a slot formation 53 and the link 51 has a clevis 54 attached thereto which straddles the slotted portion of the rod and carries a pin 55 which extends through the slot 53 and moves freely between opposite ends of the slot. The control mechanism further comprises a bracket 57 bolted to the top of the girder 10 and which has an upright section on which a shaft 58 is rotatably journaled. The shaft 58 has a crank member 60 attached at one end, which crank member includes arms 61, 62 having eyes at the ends thereof and link 51 is attached to the end of arm 61 by a clevis and bolt 63. In the form of construction shown, the end of crank arm 62 extends over the link 51 and engages it to limit counterclockwise rotation of the crank member as viewed in Figs. 1 and 4. In the event it is desirable to provide an interlock mechanism at the end of bridge A opposite to that shown, a link similar in function to link 51 could be connected with arm 62. The shaft 58 is oscillated to shift the link 51 and consequently rods 28, 29 and lock member 26 by a lever or beam 65 attached thereto which has operating chains or cables 66, 67 attached at opposite ends which may be alternately pulled by the operator. Preferably hand grips 68 are provided on the chains 66, 67 and the bridge operator may propel the bridge along its runway by pulling on the chains.

Alternatively, link 51 could be shifted by means other than manual means.

The crank arms 61, 62 are preferably disposed at less than 180° relative to one another so that when lever 65 is tilted to the position shown in Fig. 4 the bias of the yoke 42 to the left created by springs 38 tends to move the crank member 60 counterclockwise and hold the arm 62 against the link 51, and when lever 65 is moved to the position shown in Fig. 1, link 51 is moved to engage pin 55 with the left-hand end of slot 53 which limits the clockwise movement of the lever 65 and crank member 60.

The lock member 26 has a catch 70 on the top thereof and is adapted to be normally restrained from moving from its retracted position, shown in Fig. 3, to its interlocking position by a trip latch 71 pivoted between the flanges 32 by a pin 72, and adapted to cooperate with the catch. In the form shown, the catch 70 comprises a bar 73

bolted to the member 26 and having the forward side tapering inwardly and downwardly. The pawl 71 is preferably formed of a plate having a hook formation 75 adapted to engage the tapering side of bar 70 to latch the lock member in its retracted position. The pawl is normally urged to latching position by a generally U-shaped spring 77 having the legs coiled about the ends of pin 72 and the yoke overlying the pawl 71 and the ends of the legs secured in pins 78 on the flanges 32.

The pawl 71 is adapted to be automatically tripped to release the member 26 as the rails 11, 20 are brought into end-to-end alignment, and in the form of the invention shown, a cam 80 is provided on the structure B which is adapted to be engaged by a finger 81 on the pawl 71 to rotate the pawl clockwise and release the hooked portion 75 from the catch 70. The cam 80 comprises a bar 83 attached to a threaded shank 84 which is threaded in a bore in the plate P. The ends of the bar 83 are turned to lie at an acute angle relative to the path of travel of the pawl finger 81 to provide camming surfaces adapted to move the finger gradually clockwise as the bridge A moves rail 11 into alignment with rail 20.

In a monorail overhead carrier system having more than one rail with which the bridge rail 11 is adapted to be aligned, each such rail has a cam like the cam 80 associated therewith. Thus, as the bridge moves rail 11 into alignment with each rail corresponding to rail 20, the pawl 71 is moved to release the member 26; however, the lock member 26 will not move to its locking position unless the control lever 65 is set in the position shown in Fig. 1.

When the bridge is to be locked on its runway with the rail 11 in end-to-end alignment with rail 20, the operator moves control lever 65 from the position shown in Fig. 4 to the position shown in Fig. 1 as the bridge approaches the rail 20, which movement shifts the link 51 to the left and pin 55 moves to the left-hand end of slot 53 of the yoke rod 46. The lock member 26 is held in its retracted position by the pawl 71, until the finger 81 thereof engages cam 80 and is moved to release the catch bar 70, whereupon the lock member is snap moved by springs 38 to interlock with the plate P. It will be apparent that the bridge operator can preset the locking mechanism prior to reaching the point of alignment of the rails and by reason of the insignificant force required to trip the pawl 71 no appreciable drag is imposed on the bridge and it may be moved slowly and evenly to the point of alignment.

Preferably, the outer face of the lock member 26 has cam surfaces 85, 86 which slope rearwardly and are adapted to cooperate with the outer edge portion of plate P to cam the lock member rearwardly or toward its retracted position should the operator inadvertently align the girders 10, 21 with the lock member in its locking position. In this event one of the cam surfaces 85, 86 engages the plate P and cams the lock member toward its retracted position thereby preventing shock and possible injury to the mechanism.

It will be seen that the lock member 26 together with rods 28, 29 and the yoke 42 move to the locking position independently of link 51 due to slot and pin connection between yoke rod 46 and link 21 so that the crank 60 and lever 65 re-

main unmoved during the automatic locking operation.

To disengage the lock member 26 from the plate P and retain it in its retracted position, lever 65 is rotated counterclockwise and link 51 is drawn to the right and moves the yoke 42 therewith, since pin 55 engages the right-hand end of slot 53, as seen in Fig. 4. As brought out previously, lever 65 is retained in the position shown by the tension of springs 38, and the lock member 26 is thereby rendered inoperative regardless of tripping of the pawl 71 by the cam 80 until such time as lever 65 is moved by the operator to the position shown in Fig. 1 which sets the locking member for operation when the pawl is next tripped. It is to be noted that the length of slot 53 is approximately that of the stroke of member 26 so that lever 65 is set in the position shown in Fig. 1 the member may move freely of pin 55 to its interlocking position.

In the form of the invention shown, pivoted stop members in the form of levers 90, 91 are provided to prevent the carrier wheels from accidentally rolling from the ends of the rails 11 or 20 and these stop levers are adapted to be automatically raised and lowered by movement of the lock member to its locking and retracted position. The lever 90 is forked and the yoke thereof is pivoted to a depending web on the member 26 by a pin 92 with the legs thereof straddling the girder 10 and normally resting on the lateral flanges of the rail 11 in the path of carrier wheels on the rail, not shown. As member 26 moves forwardly to interlock with plate P, the yoke portion of the forked lever 90 strikes the edge of plate P and swings the lever upwardly about its pivot as shown in Fig. 1. Two stop levers 91 are pivoted to plate P on opposite sides thereof by a pin 94 and these levers each has a lug 95 which is engaged by the member 26 as it moves forwardly, to swing the levers upwardly as shown in Fig. 1. If desired, these stop levers may be omitted, or other suitable stops may be provided.

Preferably plate P is formed independently of the girder 21 which enables it to be conveniently and accurately machined to receive the components of the latching mechanism and an electrical trolley, etc., if desired. The plate is then attached to the girder 21 as by welding, either before or after one or more of the parts carried thereby are assembled thereto. Alternately, the plate P could be eliminated and the parts of the interlock mechanism carried thereby could be attached to the girder 21, which of course would then be coextensive with rail 20.

It will be seen that the objects and the advantages enumerated as well as others have been achieved, and that there is provided an overhead monorail system having locking mechanism which requires a negligible amount of force of the traveling bridge to actuate the same so that the bridge may be gradually and smoothly brought into alignment with carrier rail structures and locked in position with a minimum of wear and shock to the loaded carriers and bridge structure, etc. Furthermore, the moving parts of the interlocking mechanism may be automatically actuated without corresponding movement of the control member therefor.

While the preferred embodiment of the invention has been described in considerable detail, I do not wish to be limited to the particular construction shown which may be varied within the scope of the invention, and it is the intention to cover hereby all adaptations, modifications and

arrangements thereof which come within the practice of those skilled in the art to which the invention relates.

Having thus described my invention, I claim:

5. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member.
10. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member.
15. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member, the last mentioned means including a cam disposed on the other supporting structure.
20. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member, the last mentioned means including a cam disposed on the other supporting structure.
25. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member, the last mentioned means including a cam disposed on the other supporting structure.
30. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member, the last mentioned means including a cam disposed on the other supporting structure.
35. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member.
40. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, a latch adapted to hold said lock member from movement to its interlocking position, and means actuated by movement of said one structure to trip said latch to release said lock member.
45. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member.
50. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member.
55. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member, the last mentioned means including a cam positioned on the other of said supporting structures and adapted to be engaged by said latch.
60. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member, the last mentioned means including a cam positioned on the other of said supporting structures and adapted to be engaged by said latch.
65. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member, the last mentioned means including a cam positioned on the other of said supporting structures and adapted to be engaged by said latch.
70. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member.
75. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member associated with said one rail and adapted to be biased to interlock with a part associated with said other rail when the rails are aligned, said lock member having a catch thereon, a latch adapted to cooperate with said catch to hold said lock member from movement to its interlocking position, and means actuated by movement of said one structure for moving said latch to release said lock member.

with said other rail comprising in combination, a lock member connected with said one rail, means to bias said lock member to interlock with a member connected with said other rail when the rails are aligned, control means to selectively render said biasing means ineffective, latch means to normally hold said lock member from moving to its interlocking position, and means actuated by movement of said rails into alignment with one another to actuate said latch means to release said lock member.

6. In an overhead carrier system having supporting structures for carrier rails one of which rails is adapted to be transported by one of said structures transversely of and into end to end alignment with another of said rails, means for securing said one rail in end to end alignment with said other rail comprising in combination, a lock member connected with said one rail, means to bias said lock member to interlock with a member connected with said other rail when the rails are aligned, control means to selectively hold said lock member from movement to its interlocking position, latch means to normally hold said lock member from moving to its interlocking position, and means to actuate said latch means to release said lock member, the last mentioned means adapted to be actuated by movement of said one structure to bring said one rail into alignment with the other rail.

7. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member connected with said one rail, means to move said lock member to interlock with a member connected with said other rail when the rails are aligned, and a control member movable between two control positions to render the second mentioned means operative and inoperative, said control member having a lost motion connection with said lock member.

8. In an overhead carrier system having supporting structures for carrier rails, one of which rails is adapted to be transported by one of said structures transversely of and into end to end alignment with another of said rails, means for securing said one rail in end to end alignment with said other rail comprising in combination, a lock member connected with said one rail and adapted to be biased to interlock with a member connected with said other rail when the rails are aligned, a latch adapted to hold said lock member from movement to its interlocking position, means actuated by movement of said one structure to bring said one rail into alignment with another of said rails to trip said latch to release said lock member, and a control member movable between two positions to hold said lock member from movement to its interlocking position and to release said lock member to move to its interlocking position, said control member having a lost motion connection with said lock member.

9. In an overhead carrier system including a carrier rail and a transfer bridge or the like having a carrier rail and adapted to transport the latter rail transversely of and into end to end alignment with the other rail, locking means for securing said rails in end to end alignment comprising in combination, a lock member on the traveling bridge adapted to interlock with a member fixed relative to the first mentioned rail when

said rails are aligned, said lock member adapted to move to locking and releasing positions, means for urging said lock member to its locking position, a latch adapted to restrain movement of said lock member into locking engagement with the other member, means actuated by movement of said transfer bridge to bring said rails into alignment to trip said latch to release said lock member, and means to selectively restrain movement of said lock member to locking position independently of said latch.

10. In an overhead carrier system having a supporting structure for a carrier rail and a transfer bridge or the like having a carrier rail and adapted to transport the latter rail transversely of and into end to end alignment with the other rail, locking means for securing said rails in end to end alignment comprising in combination, a lock member on the supporting structure and a lock member on the traveling bridge adapted to interlock with one another when said rails are aligned, one of said lock members adapted to move relative to the other to locking and releasing positions, means for urging said one lock member to its locking position, a latch adapted to restrain movement of said one member into locking engagement with the other member, means to automatically operate said latch when said rails are substantially aligned to release said one lock member, and means to selectively restrain movement of said one member to locking position independently of said latch.

11. In an overhead carrier system having a supporting structure for a carrier rail and a transfer bridge or the like having a carrier rail and adapted to transport the latter rail transversely of and into end to end alignment with the other rail, locking means for securing said rails in end to end alignment comprising in combination, a lock member on the supporting structure and a lock member on the traveling bridge adapted to interlock with one another when said rails are aligned, one of said lock members adapted to move relative to the other to locking and releasing positions, means for urging said one lock member to its locking position, a latch adapted to restrain movement of said one member into locking engagement with the other member, means to automatically operate said latch when said rails are substantially aligned to release said one lock member, and means to selectively restrain movement of said one member to locking position independently of said latch, the last mentioned means including a control member having lost motion connection with said one lock member.

12. In an overhead carrier system having a supporting structure for a carrier rail and a transfer bridge or the like having a carrier rail and adapted to transport the latter rail transversely of and into end to end alignment with the other rail, locking means for securing said rails in end to end alignment comprising in combination, a lock member on the supporting structure and a lock member on the traveling bridge adapted to interlock with one another when said rails are aligned, one of said lock members adapted to move relative to the other to locking and releasing positions, means for urging said one lock member to its locking position, a latch adapted to restrain movement of said one member into locking engagement with the other member, means to automatically operate said latch to release said one lock member when said rails are moved into substantial alignment, and means to selectively restrain movement of said one member to locking

position independently of said latch, the last mentioned means including a control member movable between two control positions and having lost motion connection with said one lock member to maintain said one lock member in inoperative position when said control member is in one position and to permit movement of said one lock member to its locking position when said control member is in its other position.

13. In an overhead carrier system having a supporting structure for a carrier rail and a transfer bridge or the like having a carrier rail and adapted to transport the latter rail transversely of and into end to end alignment with the other rail, locking means for securing said rails in end to end alignment comprising in combination, a lock member on the supporting structure and a lock member on the traveling bridge adapted to interlock with one another when said rails are aligned, one of said lock members adapted to move relative to the other to locking and releasing positions, means for urging said one lock member to its locking position, a latch adapted to normally restrain movement of said one member into locking engagement with the other member, means actuated by relative movement between said bridge and supporting structure to automatically operate said latch to release said one lock member when the rails are in alignment, and means to selectively restrain movement of said one member to locking position independently of said latch.

14. In an overhead carrier system having a supporting structure for a carrier rail and a transfer bridge or the like having a carrier rail and adapted to transport the latter rail transversely of and into end to end alignment with the other rail, locking means for securing said rails in end to end alignment comprising in combination, a web on the supporting structure, a notched member

on the traveling bridge adapted to move between two positions to engage and disengage said web to lock the bridge with the supporting structure when said rails are aligned, means for urging said member to its engaging position with said web, a latch adapted to hold said member in position out of engagement with said web, means to automatically operate said latch to release said member when said transfer bridge is moved to substantially align said rails, and means to selectively move said member to its disengaging position.

15. In an overhead carrier system having a supporting structure for a carrier rail and a transfer bridge or the like having a carrier rail and adapted to transport the latter rail transversely of and into end to end alignment with the other rail, locking means for securing said rails in end to end alignment comprising in combination, a web on the supporting structure, a notched member on the traveling bridge adapted to move between two positions to engage and disengage said web to lock the bridge with the supporting structure when said rails are aligned, means for urging said member to its engaging position with said web, a latch adapted to hold said member in position out of engagement with said web, means to automatically operate said latch to release said member when said transfer bridge is moved to substantially align said rails, and means to selectively move said member to its disengaging position, said latch operating means having a lost motion connection with said member whereby said member may be held in its web disengaging position by said latch when the last-mentioned means is operative to permit movement of said member to its web engaging position.
